[57] CLAIM

The ornamental design for a toothpaste dispenser or the like, as shown and described.

DESCRIPTION

FIG. 1 is a top, front, and left side perspective view of a toothpaste dispenser or the like showing my new design;

FIG. 2 is a left side elevational view thereof, the right side being a mirror image of that shown;

FIG. 3 is a bottom plan view thereof; and

FIG. 4 is a rear elevational view thereof.

FIG. 1

FIG. 2

FIG. 4

FIG. 3
